S. G. Fischer,

Attorney.

UNITED STATES PATENT OFFICE.

IRA J. TATUM, OF KANSAS CITY, MISSOURI.

FIREARM.

Application filed January 20, 1927. Serial No. 162,317.

My invention relates to fire-arms of the shot gun and rifle types and one object is to provide a fire-arm of this character having the appearance of and which is capable of being used as a cane or walking-stick.

A further object is to provide a fire-arm embodying novel mechanism of relatively simple and inexpensive construction and which is reliable in operation.

In order that the invention may be fully understood reference will now be had to the accompanying drawings, in which:

Fig. 1 is a broken longitudinal sectional view of the fire-arm which is charged and ready for firing.

Fig. 2 is a broken longitudinal section of the fire-arm with the stock broken away and the empty shell of the cartridge being ejected.

Figs. 3, 4 and 5 are slightly enlarged cross sectional views taken on lines 3—3, 4—4 and 5—5, respectively, of Fig. 1.

Fig. 6 is a cross section on line 6—6 of Fig. 2.

Fig. 7 is a fragmentary plan view showing a portion of the gun barrel and a slidable sleeve mounted thereon.

Fig. 8 is a fragmentary plan view of a portion of the frame, the trigger, and a safety catch.

Fig. 9 is a fragmentary view partly in section of a modified form of stock and trigger mechanism.

Referring in detail to the different parts, 2 designates the tubular frame of the fire-arm, 4 the barrel, and 6 the stock, which latter is preferably in the form of a cane handle and has a forwardly projecting reduced terminal 8 removably secured within the rear end of the frame 2 by suitable means such as a screw 10.

The barrel 4 has a chambered breech 12 for the reception of a cartridge such as designated by the character A, which may be loaded with either a bullet or shot as preferred. The barrel 4 has an integral rearwardly extending tubular extension 14 in which the reduced forward end of the frame 2 is secured by suitable means such as screws 16. The tubular extension 14 has a longitudinal slot 18 in its lower portion through which the breech 12 of the barrel 4 can be loaded with the cartridge and through which the empty shell of the cartridge can be removed.

20 designates a breech block for closing the slot 18 and reliably holding the cartridge

within the breech 12. The breech block 20 is hinged or pivotally connected at its forward end to the breech 12 as indicated at 22, so that it may drop to uncover the slot 18, but is normally held in closed position by a sleeve 24 which is slidably mounted upon the frame 2 and the extension 14 and which is capable of performing other functions hereinafter referred to in addition to holding the breech block 20 in closed position.

The breech block 20 has a longitudinal bore 26 which is in axial alinement with the bore of the barrel 4 when the breech block 20 is in closed position as shown by Fig. 1. The bore 26 is provided with a firing pin 28 which is operably held in place by suitable means such as a screw 30 threaded into the side of the breech block 20 and projecting between two circumferential shoulders 32 and 33 upon the firing pin 28 for limiting the movement of the latter. A coil spring 34 pressing against the shoulder 32 and a shoulder 36 near the forward portion of the bore 26 normally holds the firing pin 28 in its backward or safety position, Fig. 1, so that its reduced forward end 38 will be spaced a short distance from the rear end of the cartridge A.

40 designates a reciprocating hammer which is wholly concealed within the frame 2 and arranged in axial alinement with the firing pin 28 when the breech block 20 is closed. The reduced rear portion of the hammer 40 is slidably mounted within a tubular guide 42 secured within the rear portion of the frame 2 by suitable means such as screws 44. The guide 42 has a longitudinal slot 46 coinciding with a similar slot 48 formed in the lower portion of the frame 2 to permit the operation of a pin 50 which is secured at its inner end to the hammer 40 for the purpose of cocking the latter and also for limiting its forward movement by contacting the forward end of said slot 46.

52 designates the main spring for propelling the hammer 40 forcibly against the firing pin 28 after said hammer 40 has been released by a vertically movable detent 54 having an opening 56 through which the rear portion of the hammer 40 projects. The opening 56 has a straight bottom portion forming a shoulder 58 for engagement with a shoulder 60 formed on the hammer 40 by recessing its under portion, see Figs. 1 and 2.

A spring 64 normally holds the detent 54 in raised position for engagement with the

shoulder 60. Said spring 64 bears at one end against the under side of the detent 54 and at its opposite end in a cup-shaped screw 66 threaded into the lower portion of the frame 2. The detent 54 is guided in its vertical movements by a trigger 68 and a pin or screw 70, which latter is secured to the lower portion of the detent 54 and projects axially through the spring 64 and the cup-shaped screw 66. The trigger 68, which is preferably in the form of a pin, as shown by Fig. 1, extends through a complementary opening in the frame 2 and is secured at its lower end to the detent 54 and provided at its upper outer end with a head or thumb piece 72.

74 designates a safety catch which is slidably held upon the rear portion of the frame 2 by the trigger 68 and a screw 76 which extends through a longitudinal slot 78 in said safety catch. A thumb piece 80 is formed integral with the rear portion of the safety catch 74 for operating the latter and a shoulder 86 is formed upon the forward end of said safety catch for engagement with the under side of the head 72 for holding the trigger 68 in safety position.

84 designates a combination injector and ejector which is slidably mounted in a longitudinal slot 87 arranged in the barrel extension 14 at a point immediately above the breech block 20. Said injector and ejector 84 has a notch 88 at its under side for receiving a portion of the flange B of the cartridge A, so that the latter can be readily inserted in the breech 12 or ejected therefrom. A rod 90 is fixed at its forward end to the injector and ejector 84 and extends rearwardly through a guide 92 in the forward portion of the frame 2. The rear end of the rod 90 is provided with a head 94 against which the rear end of a coil spring 96 presses, the forward end of said spring bearing against the guide 92 for the purpose of retracting the injector and ejector 84 with the empty shell when the breech block 20 is opened.

In practice the gun may be loaded by grasping the sleeve 24 and pushing the same backwardly to permit the breech block 20 to swing to open position. The forward end of the cartridge is then inserted in the breech 12 while the flange B is placed in the notch 88 of the injector and ejector 84, which is then pushed forwardly until the cartridge flange B contacts the breech 12. The breech block 20 is then closed and secured in such position with the sleeve 24 which is shoved forwardly against the breech 12. When the sleeve 24 is moved rearwardly to allow the breech block 20 to open as hereinbefore stated, said sleeve 24 contacts the pin 50 and pushes the latter rearwardly with the hammer 40 until the shoulder 60 passes slightly to the rear of the detent 54, which latter is imme-

ately pushed upwardly in front of said shoulder 60 by the spring 64 to hold the hammer 40 in cocked position. The sleeve 24 also in its backward movement contacts and pushes the safety catch 74 rearwardly until the shoulder 86 engages under the head 72 of the trigger 68 which is thereby held in safety position. In order to fire the gun it is only necessary to advance the safety catch 74 with the thumb 80 until the shoulder 86 passes from beneath the head 72, whereupon the trigger 68 may be depressed to release the hammer 40 which is propelled forwardly by the main spring 52 and causes the firing pin 28 to impinge against and explode the cartridge.

From the foregoing description it is apparent that as the hammer 40 is wholly concealed within the frame 2 and only the head 72 of the trigger 68 is visible that the gun will closely resemble a cane. However, when desired the stock 6 can be replaced with a stock 6^a, Fig. 9, so that the gun may be fired from the shoulder. When the stock 6^a is used a supplemental trigger 68^a is also preferably provided. Said supplemental trigger 68^a is mounted upon a pivot 98 at the underside of the frame 2^a so that said trigger will be out of the line of sight when aiming the gun. The forward end of the trigger 68^a is operably connected to a pin 70^a which projects into the frame 2^a and is connected to the detent 54^a so that when the trigger 68^a is drawn backwardly it will pull the pin 70^a downwardly and cause the detent 54^a to release the hammer 40^a.

While I have shown two forms of the invention I reserve all rights to such other forms as properly fall within the spirit and scope of the invention as claimed.

Having thus described my invention, what I claim and desire to secure by Letters Patent, is:

1. In a fire arm of the character described, a barrel having a tubular extension with a slot therein for the passage of ammunition, a breech block hinged to said barrel and adapted to enter said slot, and a sleeve slidably mounted upon the tubular extension and adapted to hold said breech block in the slot. 110

2. In a fire arm of the character described, a barrel for holding ammunition and provided with a tubular extension firing mechanism associated with said extension for exploding the ammunition, means for holding said firing mechanism in retracted position, a safety device for holding said means in cocked position, and a sleeve slidably mounted upon the tubular extension and adapted to move said safety device to active position. 120

3. In a fire arm, a barrel having a tubular extension with a slot therein for the passage of ammunition, a breech block operably connected to said barrel and adapted to close said slot, firing mechanism associated with 130

- said extension for exploding the ammunition, means for holding said firing mechanism in retracted position, a safety device for holding said means in cocked position, and a 5 slidable member associated with said tubular extension for moving said safety device to active position and permitting the breech block to open the slot.
4. In a fire arm, a barrel having a tubular extension with a slot therein for the passage of ammunition, a breech block operably connected to said barrel and adapted to close said slot, firing mechanism associated with the tubular extension and said breech block 10 for exploding the ammunition, means for holding said firing mechanism in retracted position, and a member associated with said tubular extension for controlling the breech block and retracting said firing mechanism.
- 15 5. In a fire arm, a barrel having a slot therein for the passage of ammunition, a tubular frame secured to said extension, a breech block operably connected to said barrel and adapted to close said slot, a firing pin 20 operably mounted within said breech block, a reciprocating hammer associated with said tubular frame for actuating said firing pin, an element secured to said hammer and projecting outwardly through a slot in the tubular frame, and a member associated with the tubular extension for controlling the breech block and engaging said element to retract the hammer.
- 25 6. In a fire arm, a barrel, a firing pin associated with said barrel, spring means for normally holding said firing pin in retracted position, a hammer associated with said firing pin for forcing the same forwardly, spring means for propelling said hammer forwardly, a vertically-movable detent having an opening through which said hammer extends, spring means for normally holding 30
- said detent in position for securing the hammer in retracted position, and a trigger for disengaging the detent from the hammer.
7. In a fire arm, a barrel having a tubular extension, a tubular frame extending rearwardly from said extension, a stock secured to the rear portion of said frame and extending at an angle to form a handle whereby the fire arm may be carried like a cane, firing mechanism enclosed within the tubular extension and said frame, a sleeve slidably mounted upon the barrel and adapted to adjust said firing mechanism to cocked position, safety means which is moved to active position by said sleeve for securing the firing mechanism in cocked position, and trigger means for releasing said firing mechanism after the safety means has been moved to inactive position.
8. In a fire arm provided with a rim, a barrel for holding a cartridge, a device adapted to engage the front and rear of said rim and be forced forwardly to carry the cartridge into the barrel, a breech block for holding the cartridge in the barrel, and spring means for retracting said device with the cartridge when the breech block is opened.
9. In a fire arm, a barrel for holding a rimmed cartridge and provided with a tubular extension having a longitudinal slot, a device slidably in said slot and adapted to engage the front and rear of the cartridge rim and be forced forwardly to carry the cartridge into the barrel, a breech block for holding the cartridge in the barrel, a rod extending rearwardly from said device, and spring means pressing against said rod for retracting the device with the cartridge when the breech block is opened.

In testimony whereof I affix my signature.
IRA J. TATUM.
